DESIGN FOR VEILING

Abraham Weinblum, New York, N. Y.

Application May 31, 1941, Serial No. 101,246

Term of patent 7 years

To all whom it may concern:

Be it known that I, Abraham Weinblum, a citizen of the United States and resident of New York city, in the county and State of New York, have invented a new, original, and ornamental Design for Veiling, of which the following is a specification, reference being had to the accompanying drawing, forming a part thereof, and which shows a plan view of the veiling.

The design comprises a veiling of diagonally ar-

ranged double squares, the corners of each square being connected by small substantially oval-shaped loops, the longer sides of said loops being comprised of a series of loose zig-zag stitches and the ends comprised of a single loose zig-zag stitch, all as shown.

I claim:

The ornamental design for veiling, substantially as shown and described.

ABRAHAM WEINBLUM.
